UNITED STATES PATENT OFFICE.

WILLIAM C. CUTLER, OF GLENDALE, CALIFORNIA, ASSIGNOR TO ISABELLA M. CUTLER,
OF GLENDALE, CALIFORNIA.

COIN CARRIER FOR MULTIPLE-VENDING MACHINES.

Application filed October 13, 1925. Serial No. 62,255.

The present invention relates to selective vending machines for either individual or stacked articles and further pertains to that type of machine which includes means for 5 eliminating slugs and foreign coins which may be employed in attempts to operate the machine.

One of the objects of the present invention is to provide a comparatively simple 10 vending machine adapted to vend articles selectively from a plurality of stacks.

Another object of the invention is to provide a vending machine in which a single 15 coin slot may be employed for a plurality of stacks of articles; whereby a single arrangement of slug detecting and eliminating devices will serve for any number of article 20 holders or for any number of stacks of articles.

20 In the vending of boxed sandwiches, for instance, it is advantageous to enable the customer to have his selection of several kinds of sandwiches. Ordinarily, where such requirements are to be met, it is customary to group several vending machines 25 in one casing with a coin slot for each machine or unit. It will also be understood that the usual slug eliminator requires appreciable space and is costly to duplicate in 30 several units. It is therefore another object of this invention to provide a machine including several vending units which are served by a single coin slot and slug eliminator.

35 Another object of the invention is to provide a multiple unit vending machine with a single coin slot, in which machine the coin is selectively carried to any selected unit, after passing thru the single coin slot.

40 I have illustrated my invention by the accompanying drawings in which:

Figure 1 is a view in front elevation of one practical embodiment of my invention.

Figure 2 is a view, on a larger scale, in 45 vertical cross section thereof.

Figure 3 is a view in section on a line 3-3 of Figure 2, taken at the right hand end of the machine.

Figure 4 is a view in section on a line 50 4-4 of Figure 2, taken at the left hand end of the machine.

Figure 5 is a view in section on a line 55 5-5 of Figure 1.

More specifically, the embodiment shown 55 is provided with a front casing wall 8 hav-

ing a sight opening 9 covered by a glass plate 10, thru which the articles 11 may be seen. The machine further includes a rear casing wall 12, end walls 13, a top wall 14 hinged to the rear wall 12 as at 14^a, and a bottom wall 15. Said walls coact to provide a casing which completely encloses the articles. The back wall 12 carries a forwardly extending tray 16 having an upright vertical partitioning wall 17 which provides a plurality of article holding spaces 18. In each space several articles of a given kind are arranged in a stack as shown, so that the machine contains several stacks of articles 11, each stack being of a different brand 70 or kind. Some of the stacks may contain thinner or narrower articles, as shown in Figure 1.

The tray 16 is provided with a raised rear portion 19 providing an inverted channel 20. Below the channel 20 there is spaced a coin retaining wall 21, horizontally disposed and provided with a plurality of forwardly directed notches 22. A coin carriage 23 is provided, capable of carrying a coin 24 slidably over the coin retaining wall 21 in upright position. The carrier includes spaced members 26 and 27 joined by a transverse end wall 28 to provide a coin holding space open at the top and bottom. 85 The rear member 27 continues above the front portion in an extension 29, and is inclined rearwardly. The front member 26 of the carriage 23 is provided with a rounded surface 30. The carriage is adapted to 90 move longitudinally with regard to the machine in the channel 20, provided in the tray 16. The carriage 23 is also adapted for transverse movement, as will be explained. When the coin is in the carriage it projects 95 above the front member 26 thereof.

The extension 29 to the rear of the member 27, is hinged to the rear member as at 32 and is yieldably compressible rearwardly against the pressure of a light spring 33 100 which normally holds the extension in the position shown.

The tray 16 is provided with a plurality of transverse slots 34 which gradually enlarge at the rear end as at 35. The rounded surface 30 of the front of member 26 of the carriage is adapted to enter any slot 34, and the rounded surface 30 thereon guides the carriage into a slot as said carriage is moved toward the front of the machine. 110

Such a slot as 34 is provided under each stack of articles. When a coin is in the carriage, as shown in Fig. 2, the upper part of the coin will engage the rear edge of an article 11 as the carriage 23 is moved forwardly. If a coin is not in place, forward movement of the carriage will not cause a package or article to be moved. The carriage can be moved forwardly only when it is alined with a slot 34; a vertical wall 36 of the tray acting to prevent such movement.

The coin retaining wall 21 is provided with apertures 37, one for and under each slot 34 and forwardly of the notches. The carriage 23 is provided with a rearwardly projecting stud 38 riding in a channel 39 carried by the back wall plate 12. From the forward member 26 of the carriage a rod 40 passes forwardly thru a slot 40^a in the front wall. Said rod is slidably guided by bearings 41 which are movable longitudinally of the machine along longitudinal rods 42. The rod 40 terminates exteriorly of the casing in a knob 43.

The front wall 8, at a point above the tray 16 turns horizontally outward as at 45 to provide a hood. A lower continuation 47 of the front wall 21 coacts with the end walls 13, rear wall 12 and bottom wall 15 respectively to provide a coin receiving space 48. Continuation 47 also coacts with hood 45 to provide the discharge chute 49 which chute opens outwardly of the casing as at 50. The machine is provided with a coin chute 51 which is directed downwardly and which begins at a slot 52 and terminates above an opening 51^a in the wall 19. Said chute may include slug eliminating devices and the like (not shown) and may include the branch chute 53 into which slugs and bogus coins (not shown) are directed. The branch chute 53 leads into a returning chute 55 which parallels the back wall 12 and returns the coin at a slot 56 on the left hand end of the machine. The coin returning slot 53 has a continuation 57 which ends horizontally as at 58, at the right hand end of the machine. The main coin chute 51 terminates as at 59 above the end 58 of the returning chute 53, so that a coin which comes thru the main chute 51, and which is not directed thru the branch chute, will fall into said returning chute 57 and be returned; unless the coin carriage 23 is positioned to receive it.

It will be apparent now that by pushing on the rod 40 longitudinally of the machine, the carriage 23 is moved toward the right until said carriage is alined with the main coin chute 51.

In such position the rear inclined extension 29 of the carriage catches the falling coin and directs it into the coin receiving slot in the carriage. The coin is now

held from falling thru the carriage, by the coin retaining wall 21. When the carriage 23 is not in proper position the coin will fall into the returning chute 57 and will be directed back to the customer. To operate the machine the rod 40 is moved to the right until the carriage is in place under the chute 51. A coin is inserted in the coin slot 52 and if it is accepted and passed by the chute it will gravitate into the carriage. The carriage is then moved by means of the rod 40 until the knob 43 on the handle is alined with the stack of packages from which it is desired to obtain an article. Now the rod 40 is pulled outwardly so that the forward member 26 of the carriage rides into the corresponding slot 34. The coin catches the lowermost article and moves it forwardly until it is pulled out from under the others. The package now tilts over the rod 40 and falls into the chute 49. As the coin slides over the coin retaining wall it rides over the notches 23 therein and the carriage cannot be moved again rearwardly so long as the coin is in place; the coin acting as a ratchet pawl to prevent return movement. When the article engaged by the coin is withdrawn from under the others of the stack the coin reaches the corresponding aperture 37 in the coin retaining wall 21 and falls into the coin receiving space 48. The machine is then ready to be operated. It will be apparent now that a coin can be used to remove only one article and it will also be apparent that I have provided for using a single coin slot in connection with several vending units.

Having described my invention what I claim as new and patentable is;

1. In a vending machine, a fixed coin chute, a coin carriage movable to any one of a plurality of selective positions; said carriage movable into position to receive a coin from said chute, a casing entirely enclosing said chute and carriage respectively, and selecting means operable externally of the casing to move said carriage into such selective positions.

2. In a vending machine, a coin chute, a coin returning chute spaced from said first named chute and disposed to receive a coin therefrom, a coin carriage movable into coin receiving position between said chutes, and a casing enclosing said chutes and coin carriage, and a selecting handle external to said casing and operatively connected to said carriage for moving same.

3. In a vending machine a plurality of vending units, a single coin chute, and a coin carriage movable to receive a coin from said chute and further movable away from said chute to any selected one of the vending units, a casing enclosing the parts named, and a handle operable externally of said casing to selectively move said carriage.

4. In a vending machine a horizontal wall, a coin carriage movable in a longitudinal path over said wall; said carriage also movable in a plurality of defined paths branching from said longitudinal path: said carriage being open at the bottom whereby a coin is held therein by said wall; said wall being provided with a plurality of apertures, one in each of said lateral paths, 10 a casing enclosing all the parts named, and a selectively operating handle external to said casing movable to control movement of said carriage; each of said apertures in said wall arranged to permit a coin to fall from said carriage when said carriage passes over any one of said apertures.
5. In a vending machine, a wall provided
- with forwardly directed notches arranged in transverse paths, a shaft extending longitudinally above said wall, a bearing slidable 20 on said shaft, a rod extended transversely above said wall and slidable laterally of the wall thru said bearing: said wall formed with apertures: one in each of said transverse paths, and an open-end coin carriage 25 fixed to said rod and movable therewith above said wall whereby the wall acts as the sole means to retain a coin from descent thru the open end coin carriage, and a fixed coin chute so disposed that the carriage may be 30 moved under it.

In testimony whereof I affix my signature.

WILLIAM C. CUTLER.
